(57) CLAIM

The ornamental design for a scoreline pattern for a golf club head, as shown and described.

DESCRIPTION

FIG. 1 is a perspective view of scoreline pattern for a golf club head;

FIG. 2 is a front view thereof; and,

FIG. 3 is a top plan view thereof.

The broken line showing is for illustrative purposes only and forms no part of the claimed design.

1 Claim, 2 Drawing Sheets

FIG. 3
